Inventor
James W. Fitzsimmons,

By Clarence A. O'Brien, Attorney

UNITED STATES PATENT OFFICE.

JAMES WILLIAM FITZSIMMONS, OF OAKLAND, CALIFORNIA.

MATRIX SCORCHER.

Application filed December 16, 1926. Serial No. 155,278.

This invention relates to an improved device to be used in newspaper work for drying and imparting a curved shape to a matrix so that the same will correspond to the curvature of a casting box in which it is located.

Broadly, the invention has reference to a structure which includes, among other parts, a curved heating and drying surface against which a moist matrix is placed, together with clamping means for maintaining the matrix in tight contact with said surface and for allowing the moisture to be driven therefrom in order to impart a substantially fixed curvature to the matrix to permit it to be more conveniently placed in position in the correspondingly shaped casting box.

More specifically, the invention has reference to a heated drum against the exterior top surface of which the moist matrix is placed, together with a substantially semi-circular clamping plate hingedly mounted on this cylinder and adapted to press the matrix firmly against the surface and to allow the moisture to escape through the apertures to a suitable source of heat in the interior of the casing. This operation will dry, iron out and shape the matrix to the correct curvature of a casting box.

Other features and advantages of the invention will become apparent from the following description and drawing.

In the drawings:

Figure 1 is a side view of a scorcher constructed in accordance with the invention,

Fig. 2 is an end elevation looking in the direction from right to left,

Fig. 3 is a cross section taken approximately upon the plane of the line 3—3 of Fig. 1.

Referring to the drawings in detail it will be seen that the reference character 1 designates a supporting stand which includes a pair of uprights composed of substantially U-shaped end frames 2 connected together by horizontal connecting bars 3. Between the depending or vertical portions of the frame are suitably shaped connecting members 4. The lower ends of said vertical portions of the frame are inturned as at 5 to provide attaching feet which may be suitably secured in place. The bight portions of the frames are curved in a dished man-

ner as at 6 for reception of the lower correspondingly curved surface of the heating drum or casing 7. This drum may be composed of an open ended cylinder with suitable end heads. Located in the lower portion of this drum and extending through the end is an appropriate fuel burner 8 with which a disposed regulating and supply means 9 is connected. Also connected to the right hand end of the drum is an exhaust pipe 10 through which the products of combustion are allowed to escape. The curvature of the surface of the drum is such as to correspond substantially with the curvature of an ordinary casting box in which a matrix is placed when casting plates. Hinged to one side of this drum as at 11 is a clamping and form plate 12 provided with a multiplicity of apertures. This plate is shaped to conform to the surface of the drum and a moist matrix (not shown) is adapted to be placed between it and said drum. The free end portion of the plate 12 is provided with a suitable hand grip 13. Attention is also directed to a baffle plate 14 on the interior of the drum and disposed over the burner pipe 8 for equally distributing the heat and to insure more efficient operation of the device.

In order to operate the device it is only necessary to light the burner and the same is ready for use. The cover is swung up and the matrix is placed on top of the cylinder and then the cover is brought down and clamped in place by friction. This operation will dry, iron out and shape the matrix to the correct curvature of the casting box into which it is subsequently disposed for the casting operation.

Persons skilled in the art to which the invention relates will no doubt obtain a clear understanding of the construction, method of use, and features and advantages of the improved device. Therefore, a more lengthy description is thought unnecessary.

While the preferred embodiment of the invention has been shown and described, it is to be understood that minor changes coming within the field of invention claimed may be resorted to if desired.

I claim:

A matrix scorcher comprising a frame, the top of which is dished, a drum seated in

and supported by said dished frame top, said drum of circular cross section and having a conduit at its ends for the passage of products of combustion, a burner in the lower portion of the drum, a baffle plate of imperforate character disposed above the burner and having its opposite edges sup-

ported on brackets in the drum and spaced from the wall of the drum, and an apertured matrix clamping plate of curved form ¹⁰ hinged to and adapted to cooperate with the curved surface of the drum.

In testimony whereof I affix my signature.
JAMES WILLIAM FITZSIMMONS.
